(57) **CLAIM**

The ornamental design for a sleeve for co-axial cable connector, as shown and described.

DESCRIPTION

FIG. 1 is a perspective view of a sleeve for co-axial cable connector showing my new design;

FIG. 2 is a side elevational view thereof, the other sides, top,
plan and bottom plan views being mirror images;

FIG. 3 is a first end view thereof; and,

FIG. 4 is a second end view thereof.

The broken lines depict environmental structure and form no
part of the claimed design.
